UNITED STATES PATENT OFFICE.

CHARLES CARSTENS, OF DENVER, COLORADO.

BEET AND COTTON BLOCKER.

No. 849,327.

Specification of Letters Patent.

Patented April 2, 1907.

Application filed June 4, 1906. Serial No. 320,211.

To all whom it may concern:

Be it known that I, CHARLES CARSTENS, a citizen of the United States, residing at the city and county of Denver, and State of Colorado, have invented certain new and useful Improvements in Beet and Cotton Blockers; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to improvements in machines for blocking or cutting out the superfluous plants of all vegetables that are planted in rows.

While the apparatus is more especially 20 intended for use with beets and cotton, it may of course be used for blocking plants of all kinds. My improved apparatus is intended to perform the blocking function very rapidly. In fact, a single machine may 25 be constructed to block a number of rows at a time. The machine shown in the drawings is intended for blocking four rows every time it is drawn across the field. It is evident, however, that the same principle may be employed 30 and that the machine will be substantially the same for any number of rows.

The invention will now be described in detail, reference being made to the accompanying drawings, in which is illustrated an 35 embodiment thereof.

In the drawings, Figure 1 is a top plan view of the machine. Figs. 2 and 3 are sections taken on the line 2 3, Fig. 1, looking in the direction of the arrow, but showing the 40 blocking mechanism in two different positions. Fig. 4 is a detail view illustrating the clutch-shifting mechanism which automatically throws the machine out of gear every time the blocker-heads are raised from the 45 operative to the inoperative position. Fig. 5 is a perspective view in detail of one of the gage shoes or plates for regulating the plane of cut of the blocker-heads. Fig. 6 is an end elevation of one of the blocker-heads.

50 The same reference characters indicate the same parts in all the views.

Let the numeral 5 designate an axle mounted on ground-wheels 6, which are normally loose on the axle. This axle is journaled in depending bearings 7, carried by the 55 framework 8, which, as shown in the draw-

ings, is composed principally of an integral metal bar comprising end members A, extending forwardly from the axle, inwardly extending members B at right angles to the members A, rearwardly-extending members C, passing rearwardly beyond the axle, and a centrally-located member D, connecting the rear extremities of the two members C. At each forward corner of this frame is located 60 an auxiliary frame member E of angular shape, which strengthens the frame and also forms a bearing for the shafts F of the two outside blocker-heads G. The frame is further provided with a front member H, connecting the two members B, and two upwardly-curved members I, secured at their extremities to the member H in front and to the member D in the rear. The tongue or draft-pole J of the machine passes between 65 the members I and is held in place by a bolt K, which passes through registering openings formed in the upper central portions of the frame members I and the rear extremity of the tongue. 70

As shown in the drawings, there are four blocker-heads G, each made fast to the forward extremity of a rotary shaft F. These shafts are all suitably journaled in the frame and are provided at their rear extremities 75 with beveled gears L, meshing with gears M, fast on the axle. The rear extremities of the two inner shafts F are journaled in a centrally-located frame member N. 80

Upon the inner extremity of the hub of 90 each ground-wheel 6 is made fast a clutch member O, adapted to coöperate with an adjacent clutch member P, splined on the axle and having a circumferential groove Q, which is engaged by the forked extremity R 95 of a shifting-lever S, fulcrumed at T. Each clutch member P is normally driven to engagement with an adjacent clutch O by a coil-spring U, interposed between the member P and the adjacent frame member C. 100 Provision is made for shifting the clutch members P inwardly, whereby they are disengaged from the clutch members O, compressing the springs U and locking the same in the disengaged position when the blocker-heads G are raised to the inoperative position. This is accomplished by means of links V, pivotally connected, as shown at W, with the shifting-levers S. The inner extremities of these links V are respectively 105 connected at upper and lower points X and Y with a lever Z, fulcrumed at 9 on the frame 110

member N. The upper extremity 9^a of this lever is adapted to engage the tongue J when the frame is raised to throw the blocker-heads G to the position shown in Fig. 1. As this is done the lever is actuated to pull both links V inwardly toward the center of the machine, whereby the levers S are actuated to throw the clutch members P inwardly and disengage the said members from the clutch members O, thus throwing the machine out of gear or into the position so that the ground-wheels rotate without moving the blocker devices.

Each blocker-head consists of a hub 10 and a number of cutters 12, connected with the hub and extending first outwardly at right angles to the shaft F, where they are bent inwardly to form an acute angle at the points 13, whereby the free extremities 14 of the teeth are nearer the axis than the bends or angles 13. By reason of this arrangement the blocking members 15 of the cutter will occupy a horizontal or approximately horizontal position when thrown to the operative position, as indicated in Fig. 3.

The entire framework is shifted from the position shown in Fig. 3 to that shown in Fig. 2, or the reverse, by operating a lever 16, fulcrumed on the tongue at 17 and provided with an auxiliary arm 18, which passes underneath a U-shaped metal loop 19, whose lower extremities are connected with the curved frame members I. The operating-lever 16 is provided with the ordinary locking-dog 20, handpiece 21, connecting-rod 22, whereby the dog 20 may be made to engage any desired notch 23 of the quadrant 24.

Forward of the blocking devices the tongue J is provided with the ordinary set of whiffle-trees 25, to which the draft-horses are hitched. In driving across the field each horse of the team would travel between the two rows of beets on opposite sides of the tongue or would travel in a path which when rearwardly extended passes between the blocker-heads of each pair when four of these heads are employed.

From the foregoing description the use and operation of my improved machine will be readily understood. When the apparatus is in use, the blocker-heads are in the position indicated in Fig. 3 and the clutch members P are thrown into engagement with the co-operating member 6, whereby as the ground-wheels rotate as the machine is driven across the field rotary motion is imparted to the blocker-heads by the gears M and L and the shaft F. As these blocker-heads rotate during the forward movement of the machine, each blocking member or cutter 15 will cut out the plants of a row for a space equal to the length of the cutter, and before the next cutter of the same head will reach the row the machine has advanced sufficiently to bring the second cutter, so to speak, slightly

ahead of the space cut by the previous cutter, thus leaving a plant between the two spaces. This is the principle of the machine. Of course it is not supposed that it will be possible to have the action of the machine so perfect that single plants only will be left after the blocking operation, since it is expected that some thinning will be required even after my machine has performed its function. All that can be expected of a machine of this kind is to perform the greater part of the blocking or thinning function required in an industry of this character.

It will be understood that as the blocker-heads are raised and lowered the framework 80 of the machine turns around the axle, since the latter passes through bearings mounted on the frame. However, since the curved frame members I are connected with the tongue J, it will be understood that the 85 tongue will be moved slightly during each raising and lowering operation; but this movement of the tongue is so small as not to interfere with the operation of the machine.

To the forward extremity of the framework is attached a number of gage shoes or plates 26, consisting of an upright part 26^a and a rearwardly-curved part 26^b, the last-named part being adapted to engage the ground when the blocker-heads are in operative position, (see Fig. 3,) and thus regulate the plane of the cut of the cutter members during the operation of the machine. These gage-plates are vertically adjustable, and to this end the upright part 26^a is provided with a vertically-disposed slot 26^c. The gage is secured to the frame of the machine by passing a bolt 26^d through this slot and securing it in place by a nut. By reason of this construction the gage may be vertically adjusted at will.

Having thus described my invention, what I claim is—

1. In a beet and cotton blocker, the combination with ground-wheels and an axle upon which the ground-wheels are loosely mounted, of a framework pivotally mounted on the axle, blocker-head shafts journaled in the framework and extending at right angles to the axle, a gearing connection between the axle and the shafts, clutch members splined on the axle and adapted to engage co-operating clutch members carried by the ground-wheels, means for shifting the framework on the axle to raise and lower the blocker-heads, and means for automatically connecting and disconnecting the said clutch members by the action of the framework as the latter is so shifted.

2. An apparatus of the class described, the combination of an axle, ground-wheels normally loose thereon and provided with clutch members, other clutch members splined on the axle, springs whose normal tendency is to throw the splined clutch mem- 125

bers into engagement with the clutch members of the ground-wheels, a framework pivotally mounted on the axle, blocker-head shafts journaled in the frame and geared to the axle, means for shifting the framework on the axle to raise the blocker-heads, means for automatically disconnecting the splined clutch members from the wheel-clutch members by the action of the framework as the latter is so shifted.

3. In apparatus of the class described, the combination with ground-wheels and an axle loose on the ground-wheels, the said wheels being provided with clutch members, other 15 clutch members splined on the axle, springs for normally throwing the splined clutch members into engagement with the wheel clutch members, a framework pivotally mounted on the axle, blocker-head shafts 20 journaled on the frame and geared to the axle, and means for shifting the splined

clutch members to disconnect them from the wheel clutch members as the framework is moved on the axle to raise the blocker-heads to the operative position, said means comprising clutch-shifting levers, links connected with these levers and extending inwardly toward the center of the machine, and a centrally-located lever with which the inner extremities of the links are connected, said levers being so arranged that as the portion of the framework forward of the axle is raised, the said lever strikes the tongue and is automatically shifted to pull the links inwardly for the purpose set forth.

25 In testimony whereof I affix my signature in presence of two witnesses.

CHARLES CARSTENS.
